UNITED STATES PATENT OFFICE.

WILLIAM RECHAB HONEYWELL, OF TORONTO, CANADA.

HOT-AIR ENGINE.

No. 820,495.

Specification of Letters Patent.

Patented May 15, 1906.

Application filed July 14, 1904. Serial No. 216,515.

To all whom it may concern:

Be it known that I, WILLIAM RECHAB HONEYWELL, inventor, a subject of the King of Great Britain, residing in the city of Toronto, in the county of York and Province of Ontario, Canada, have invented certain new and useful Improvements in Hot-Air Engines, of which the following is a specification.

My invention relates to improvements in hot-air engines and one object of my invention is to design a simple and comparatively cheap engine of this class that will develop the maximum amount of power.

Another object is to design a particular form of valve and port opened and closed by same.

A still further object is in my preferred form of invention to design a particular feeding-plug so that fuel may be fed to the combustion-chamber at all times; and it consists, essentially, of the cylinder provided with an exhaust-port and an intake-port, and the piston connected to the engine-shaft, heating means for the air, and a pressure-valve operated to open and close the port between said heating means and said cylinder, and other details of construction, as hereinafter more particularly explained.

My invention is of course applicable to two-cycle or four-cycle engines.

Although I preferably heat the air by means of fuel—such as wood, coal, or charcoal—fed into the combustion-chamber, I of course may heat the air by means of electricity or liquid fuel. When fuel is used of the nature above mentioned in the heating-chamber, the fire is built therein in the ordinary manner, and as there will always be a goodly supply of oxygen within the said combustion-chamber the fuel will be consumed. It will be understood by one skilled in this art that the combustion is a continuous one.

Figure 1 is a longitudinal vertical section through my engine. Fig. 2 is a horizontal section on the line *a b*, Fig. 1. Fig. 3 is an enlarged plan view of part of the cylinder, showing feed and exhaust ports. Fig. 4 is a vertical cross-section on the line *c d*, Fig. 3. Fig. 5 is an enlarged vertical section through the pressure-valve.

In the drawings like characters of reference indicate corresponding parts in each figure.

A is the cylinder, in which operates the piston *B*, connected by its rod *C* with the shaft

D, on which is the fly-wheel *D'*. By means of an induction-valve *E* air passes into the crank-case *F* during inward movement of the piston *D*, and is forced by the outward movement of same through the port *G* in said crank-case and into the conduit *I* and thence into the cylinder *A* through the ports *H*. As the piston goes inward the ports *H* are closed and the fresh air is forced through the port *J* into the combustion or heating chamber *K* by the opening of the valve *L* of said port. The compressed air always enters the port *J* below the end of the valve *L*, and consequently opens same. As soon as the air-pressure falls below the strength of the spring *M* the valve *L* is closed, thus retaining the air within the chamber *K*. When the engine is first started, it will be understood that it acts merely as an air-pump, so as to get the required pressure of air within the chamber *K*. When the required air-pressure is reached, the fresh supply of air into the chamber *K* by the inward movement of the piston *B* will raise the pressure of the air high enough so that immediately the said piston has reached the limit of its inward movement, the port *J* being open, the air-pressure within the chamber *K* will be so great as to hold the valve *L* up, and thus permit a quantity of hot air to pass into the cylinder *A* and force the piston outward, thus doing work. As soon as the piston reaches the limit of its outward movement the air escapes from said cylinder through the exhaust-ports *N* into the exhaust-pipe *O*. Of course when the pressure within the chamber *K* falls below a certain point the valve *L* closes the port *J*. The closing of the port *J* will of course take place before the exhaust-ports *N* are opened. As the ports *H* and *N* are preferably opened and closed simultaneously, it will be understood that because of its greater pressure the spent air will exhaust through the ports *N*, and the fresh air as soon as the pressure within the cylinder *A* is low enough passes thereto through the ports *H*, which open from the conduit *I*. *I'* is any suitable cap for covering the conduit *I* and is suitably secured to the cylinder *A*. As will be seen from Fig. 1, the end *l* of the valve *L* is below the receiving end *j* of the part of the port *J* between said valve and said chamber *K*, so that no matter how great the air-pressure may be within said chamber the valve *J* cannot be opened by same.

The lower end of the valve L operates in any suitable chambered construction P, secured to or forming part of the cylinder A. Screwing onto the upper part A' of the same 5 casing that forms the combustion or heating chamber is a housing Q, in which the upper end of the valve L operates. In the construction shown I provide the said valve with a spindle m, on which and within said housing 10 Q is contained the spring M, that keeps the valve L in normal position. By means of a chambered cap S, screwing onto the top of the housing Q, the tension of the spring M is regulated. The spindle m passes up through 15 the cap S and the bracket T, suitably secured to the engine-frame. By means of any suitable adjustable stops o and o' on the spindle m the range of movement of the valve L is regulated. Within the housing Q is a gland 20 U between which and the gland V is packing W, and between the gland V and the construction P is packing X.

Held on the upper part of the chamber K is a hollow circular tapered plug 2, by means 25 of which the fuel is fed thereinto. The fuel is placed in the chamber 3, and by means of its shank 4 the said plug is turned until the contents of said chamber 3 are emptied into said chamber. The plug is then returned to normal 30 position. By this construction of plug it will be understood that fuel can be fed at all times into said chamber. By means of the gland 5 screwing into the cap 6, suitably secured to said chamber K, said plug is held 35 snugly in place.

In order that the chamber K may always withstand the pressure, I surround same with a water-casing 7 (suitably secured at its lower edge to the bottom 8, to which bottom 40 is suitably secured the chamber K) and suitably secured at its upper edge to the upper part A' of the combustion-chamber casting. The inner end of the cylinder A extends within the casing 7 (to which casing it is suitably secured) and is of course surrounded by 45 the water.

The gland V is provided with holes v, which register with the slots or holes v' in the hollow valve L, so that water may pass into 50 said valve.

Although not absolutely necessary, I provide the casing 7 with any suitable steam-dome 9, into which extends the pipe 10, opening at its lower end into the chamber K. 55 and provided with a check-valve 11 to prevent air escaping therethrough. The upper end of the pipe 10 is open and is provided with any suitable hood 12, by means of which only steam may pass thereinto. From this 60 description it will be understood that I may use steam with the hot air if I find it of any advantage.

By means of any suitable plug K' ashes may be removed from the chamber K.

65 I do not confine myself to using my im-

provements in engines only, nor do I confine myself to the construction herein shown and described, as same can be altered in many ways without departing from the spirit of my invention.

70

What I claim as my invention is—

1. In a hot - air engine, the combination with the cylinder provided with air-intake ports and an exhaust-port and a motive-fluid feed-port, and piston working in the 75 cylinder, of means for heating air fed into said cylinder through said feed-port, and a valve controlling said feed-port and opened by the pressure of air in said cylinder.

2. In a hot - air engine, the combination 80 with the cylinder provided with air-intake ports and an exhaust-port and a motive-fluid feed-port, and piston working in the cylinder, of means for heating air fed into said cylinder through said feed-port, and a 85 spring-controlled valve controlling said feed-port, and opened by the pressure of air in said cylinder.

3. In a hot - air engine, the combination 90 with the cylinder provided with air-intake ports and an exhaust-port and a motive-fluid feed-port and piston working in the cylinder, of means for heating air fed into said cylinder through said feed - port, and a valve controlling said feed-port and opened by the pressure of air in said cylinder, the lower end of 95 said valve normally resting above the part of said feed - port immediately leading from said cylinder, and normally below the other part of said feed - port between same and said 100 heating means.

4. In a hot - air engine, the combination with the cylinder provided with air-intake ports and an exhaust-port and a motive-fluid feed-port and piston working in the cylinder, 105 of means for heating air fed into said cylinder through said feed-port, and a spring-controlled valve controlling said feed-port and opened by the pressure of air in said cylinder, the lower end of said valve normally resting 110 above the part of said feed - port immediately leading from said cylinder, and normally below the other part of said feed - port between same and said heating means.

5. In a hot - air engine, the combination 115 with the cylinder provided with air-intake ports and an exhaust-port, and a motive-fluid feed-port opening from its head, the piston in said cylinder, and the crank-case provided with a valve-controlled intake - port 120 and a feed - port communicating with the intake - ports of said cylinder, of a combustion-chamber connected to said cylinder by said first - mentioned feed - port; a spring - controlled valve for controlling said first - mentioned feed - port, the lower end of said valve 125 normally resting above the part of said first - mentioned feed - port immediately leading from said cylinder, and normally below the other part of said first - mentioned feed - port 130

between same and said combustion-chamber, and means for feeding fuel into said combustion-chamber.

6. In a hot-air engine, the combination with the cylinder provided with air-intake ports and an exhaust-port, and a motive-fluid feed-port opening from its head, the piston in said cylinder, and the crank-case provided with a valve-controlled intake-port and a feed-port communicating with the intake-ports of said cylinder, of a combustion-chamber connected to said cylinder by said first-mentioned feed-port; a spring-controlled valve for controlling said first-mentioned feed-port, the lower end of said valve normally resting above the part of said first-mentioned feed-port immediately leading from said cylinder, and normally below the other part of said first-mentioned feed-port between same and said combustion-chamber; means for limiting the movement of said spring-controlled valve and means for feeding fuel into said combustion-chamber.

7. In a hot-air engine, the combination with the cylinder provided with air-intake ports and an exhaust-port, and a motive-fluid feed-port opening from its head, the piston in said cylinder, and the crank-case provided with a valve-controlled intake-port and a feed-port communicating with the intake-ports of said cylinder of a combustion-chamber connected to said cylinder by said first-mentioned feed-port; a casing surrounding said combustion-chamber and designed to contain water; a spring-controlled valve for controlling said first-mentioned feed-port, the lower end of said valve normally resting above the part of said first-mentioned feed-port immediately leading from said cylinder, and normally below the other part of said first-mentioned feed-port between same and said combustion-chamber; means for limiting the movement of said spring-controlled valve, and means for feeding fuel into said combustion-chamber.

8. In a hot-air engine, the combination with the cylinder provided with air-intake ports and an exhaust-port, and a motive-fluid feed-port opening from its head, the piston in said cylinder, and the crank-case provided with a valve-controlled intake-port

and a feed-port communicating with the intake-ports of said cylinder, of a combustion-chamber connected to said cylinder by said first-mentioned feed-port; a casing surrounding said combustion-chamber and designed to contain water; a spring-controlled hollow valve provided with openings through which the water may pass thereinto, for controlling said first-mentioned feed-port, the lower end of said valve normally resting above the part of said first-mentioned feed-port immediately leading from said cylinder, and normally below the other part of said first-mentioned feed-port between same and said combustion-chamber; means for limiting the movement of said spring-controlled hollow valve, and means for feeding fuel into said combustion-chamber.

9. In a hot-air engine, the combination with the cylinder provided with air-intake ports and an exhaust-port, and a motive-fluid feed-port opening from its head, the piston in said cylinder, and the crank-case provided with a valve-controlled intake-port and a feed-port communicating with the intake-ports of said cylinder, of a combustion-chamber connected to said cylinder by said first-mentioned feed-port; a casing surrounding said combustion-chamber and designed to contain water; a spring-controlled hollow valve provided with openings through which the water may pass thereinto for controlling said first-mentioned feed-port, the lower end of said valve normally resting above the part of said first-mentioned feed-port immediately below the other part of said first-mentioned feed-port between same and said combustion-chamber; means for limiting the movement of said spring-controlled hollow valve; means for feeding fuel into said combustion-chamber, and a pipe opening into said combustion-chamber from said casing containing the water, and a check-valve in said pipe.

In testimony whereof I have signed my name to this specification in the presence of two subscribing witnesses.

WILLIAM RECHAB HONEYWELL.
